UNITED STATES PATENT OFFICE.

FRANK G. HOLLAND, OF CLEVELAND, OHIO, ASSIGNOR TO THE GLOBE MACHINE & STAMPING COMPANY, OF CLEVELAND, OHIO.

GRINDING-MACHINE.

1,356,068.

Specification of Letters Patent.

Patented Oct. 19, 1920.

Application filed August 20, 1917, Serial No. 187,308. Renewed September 9, 1920. Serial No. 409,291.

To all whom it may concern:

Be it known that I, FRANK G. HOLLAND, a citizen of the United States, residing at No. 1250 W. 76th St., city of Cleveland, in the county of Cuyahoga and State of Ohio, have invented a new and useful Improvement in Grinding-Machines, of which the following is a specification, the principle of the invention being herein explained and 5 the best mode in which I have contemplated applying that principle, so as to distinguish it from other inventions.

This invention relates to a grinding machine and more particularly to one of the 15 rotary surface type. The exemplifying structure disclosed by the drawings is especially adapted for grinding rings such as clutch rings or variously sized washers.

My object has been to design a structure 20 differing in several fundamental respects whereby to achieve the following list of advantages, namely:

1. To strengthen and thereby insure precision during the operative engagement. 25 This is accomplished by reversing one of the relative movements as between the work and tool, that is to say, the grinding wheel rotates in a fixed position while the work support moves. The advantage consists in 30 being thus enabled constantly to hold the tool spindle in rigid alinement by avoiding the excessive leverage which occurs when the same is moved parallel to its own axis.

2. To increase the working capacity of 35 the machine. This is made possible owing to a duplex arrangement, either part of which may however, if desired, be operated independently of the other. By this means the operator may prepare for one job on 40 the idle part and at the same time carry on the performance of the other.

3. To automatically control both a lifting and traverse movement of the work support relative to the position of the tool, and to 45 provide an automatic adjustment as well, in order uniformly to distribute the abrading action.

4. To eliminate sliding surfaces and effectively protect the circular working parts 50 against the entry of grit and dust.

For the performance of the class of work for which the machine embodying my invention is peculiarly useful it is either necessary or desirable to provide four primary operative movements:

1. High speed rotation of the abrading wheel or wheels.
2. Rotation of the work support.
3. Feed of the work toward the grinding wheel.
4. Travel of the work in a direction transverse to the feed.

All of these operations are, of course, preferably automatic and are capable of being so accomplished with my machine. Besides 65 the foregoing, it is desirable to provide various adjustments whereby to control the range of action or "throw". Accordingly, I have provided means for regulating the amount of feed, means for automatically 70 causing a cessation of the automatic feed, means for timing the initiation of the automatic feed movement, and duplex means for varying the range of travel of the work across the grinder, such travel being in fact 75 an oscillatory movement.

Besides the preceding enumeration, I have aimed to construct a machine and actually succeeded in so doing which will be neat and trim in appearance, smooth and firm in 80 action and reliable in operation.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the 90 scope of the claims hereunto appended.

Adverting to the drawings:—

Figure I is an elevation of a grinding machine embodying my invention.

Fig. II is a top plan view of Fig. I. 95

Fig. III is a mainly vertical section on line III—III of Fig. I.

Fig. IV is a horizontal section on line IV—IV of Figs. I and III.

Fig. V is a section on line V—V of Fig. I. 100

Fig. VI is a vertical cross section through a median plane of the lower portion of the machine on line VI—VI of Figs. I and VII.

Fig. VII is a transverse vertical section 5 on line VII—VII of Fig. VI.

Fig. VIII is a vertical section taken on line VIII—VIII of Fig. VI.

Fig. IX is a section taken on line IX—IX of Fig. VII, a part of the casting being 10 broken away.

A suitable bed 1 supports at its middle an upright frame 2 which in turn carries at its top horizontal bearings 3 in which a spindle 4 is mounted. Secured to opposite 15 ends of the spindle 4 are a pair of grinding wheels 5. These are adapted to be driven at a high speed by means of a pulley 6 which is to be driven from a countershaft not shown. It should be understood that in my 20 machine the wheels 5, except for their rotary movement, are fixed against movement in any other direction.

Supported in suitable bearings 7 on one 25 side of the machine, namely, the front side as viewed in Fig. I is a horizontal shaft 8 at one end of which are fast and loose pulleys 9 and 10 respectively and at the intermediary point such shaft carries a cone pulley 11. Two of the bearings 7 are located 30 between the pulleys while the third is mounted at the upper end of one of two duplicated frame members 12 which is intended to support the work piece above a water guard 13. Inasmuch as the construction 35 of each end of the machine is identical only one end will be specifically described and in fact the opposite end which is not shown supplied with a water guard.

Rotation of chuck.

40 The opposite side of the machine is similarly provided with a pair of bearings 14 in which is mounted a shaft 15 carrying at one end fast and loose pulleys 16 and 17 and at the intermediary point a cone pulley 18, all as shown in Fig. II. The opposite end of the shaft 15 extends through a hollow member 19 in alignment with the bearings 14 and forming an upper part of a frame 45 structure corresponding to the structure 12 at the opposite end. Directing attention to Fig. III it will be seen that interiorly of the structure 19 the shaft 15 carries a bevel gear 20 which meshes with a bevel gear 21 at the upper end of a vertical shaft 22 which extends through the center of oscillation of a swinging work support 23. Such support is shown in Fig. III to be mounted upon a ball bearing 24. The lower end of the shaft 55 22 is a cone pulley 25 operatively connected by means of a belt 26 with another cone pulley 27 at the lower end of a short shaft 28. Keyed to the latter is a pinion 29 which drives a gear 30 having a long sleeve 31 ro-

tating in a bushing 32. The gear 30 is 65 splined to a chuck spindle 33 on the upper end of which a magnetic chuck 34 is mounted for rotary movement on the ball bearings 35. The lower side of the chuck 34 is provided with the usual contact rings 36 and 70 37 which are in turn connected with an electrical terminal 38. The chuck carries a downwardly extending flange 39 in telescopic relation with the proximate upper end of the swinging frame 23 in order to 75 preclude the entrance of grit or dirt. A work piece W which may be considered to be a clutch ring is shown supported upon the upper surface of the chuck in a position to be operated upon by the grinding wheel 5 80 after adjustment in the manner to be herein-after described. As should now be readily understood the rotation of the chuck 34 may be continuously effected when the fast pulley 16 is caused to rotate owing to the 85 fact that the vertical shaft 22 is in line with the center of intended oscillation of the chuck while such parts as are to be swung back and forth may be bodily so moved because they are flexibly connected with the 90 shaft 22.

Cross travel of chuck.

In order to accomplish the desired movement of the chuck relative to the plane of 95 the wheel 5 power is taken from the cone pulley 11 by means of a belt 40 to a lower cone pulley 41 as appears in Fig. I. The pulley 41 is fixed to one end of a worm shaft 42 seen in Figs. I and VI, which shaft transmits its rotation to a worm wheel 43 mounted on one end of a shaft 44. The other end of such shaft carries a heart-shaped grooved cam 45 as shown in Figs. VI and VII. This cam in its rotations causes a roller 46 105 to run around in its groove. The roller 46 is mounted for movement on a short shaft 47 shown in Fig. IX which is carried by a hollowed lever structure 48 in which latter a plunger 49 is mounted for adjustment as 110 will be hereinafter described. The structure 48 and therefore the plunger 49 are pivotally mounted upon a shaft 50 shown in Figs. VII, VIII and IX so that the lower end of the structure 48 moves in and out by 115 reason of the roller following each contour of the cam. The upper end of the plunger 49 will be likewise oscillated back and forth. A link 51 has a universal joint with the upper end of the plunger 49 by means of a 12 clevis 52 which is pivoted in transverse directions of both plunger and link. The other end of the link 51 has a ball and socket joint connection at 53 with a portion 54 of the frame that carries the chuck 12 spindle. This connection is most clearly seen in Fig. VII though the link itself may also be seen in Fig. I. As should now be

readily understood power transmitted to the shaft 44 causes an actuation of the link 51 back and forth and consequently an oscillation of the frame 54 about the axis 5 of the vertical shaft 22 and upon the roller bearings 24. Directing attention to Figs. VIII and IX it will be noticed that one end of the shaft 50 carries a worm gear 55 which may be actuated by a worm 56 on a short shaft 57 extending through a suitable bearing 58. The other end of the shaft 57 carries a knob 59 by means of which its movement may be effected for the purpose to be now described. The opposite end of the pivot shaft 50 has secured to it a spur pinion 60 adapted to mesh with rack teeth 61 cut out of one side of the plunger 49 as may be seen in Fig. VII. By this means an adjustment of the knob 59 causes a movement of the plunger 49 and in consequence a greater or less distance between the pivot shaft 50 and the elevi 52, whereby the oscillatory travel of the link is either increased or decreased and the movement of the chuck across the grinding wheel similarly increased or decreased to suit the various widths of rings which it is proposed to grind. As a further means of adjustment, according to the diameter of the rings which are to be ground, I have arranged an adjustment of the ball and socket connection 53 along the link 51 by means of any approved type of clamp 62. In this manner the throw of the work may be located at the proper position preparatory to making the more delicate adjustment by means of the knob 59.

Owing to the latter, considerable overhang of the oscillatory chuck supporting frame, I have thought it advisable to provide auxiliary supporting means in the form of an arcuate track 63 in order to relieve the bearings 24 of some of the strain. The track 63 is clearly shown in Figs. III and IV and is adapted to be traversed by a roller 64 secured at the bottom of a pin 65 which is yieldingly mounted for vertical movement by means of a spring 66 located in a depending portion 67 of the frame.

50 *Upward feed of chuck.*

In following the description of the mechanism for accomplishing the automatic feed of the chuck toward the wheel 5 consideration of Figs. I, III and V is suggested. The chuck supporting bearings 35 are in turn supported on a flanged sleeve 68 which surrounds but is spaced from the spindle 33. Only the lower end of the sleeve 68 is fastened with an exterior thread 69 with which a nut 70, having only its upper end internally threaded at 71, is operatively associated. The nut 70 is held against actual movement in the casting, whereas the sleeve

68 is free to move up and down. A gear 65 72 is firmly secured to a lower tapered portion of the nut 70 and held in place thereon by means of a lock nut 73. This gear is adapted to be rotated by a pinion 74 carried upon a short vertical shaft 75 at the upper end of which is a bevel gear 76 in mesh with another bevel gear 77 on the inner end of a shaft 78. Both the shaft 75 and the shaft 78 are mounted in suitable bearings formed in a supporting bracket 79. Near the opposite end of a horizontal shaft 78 is a hubbed ratchet 80 around the hub of which an actuating arm 81 is loosely mounted. Pivoted to the upper end of the actuating arm is an actuating pawl 82 adapted to advance the ratchet a given number of notches, whenever the lower end 83 of the arm is moved to the left as viewed in Fig. I. The end 83 is so moved during the oscillation of the chuck frame whenever it reaches one limit of its travel by reason of coming into engagement with an adjustable stop 84 which is adapted to be fixed in various positions along a bed flange 85 as will be clearly perceived by inspection of Figs. I and III. As the shaft 78 is thus intermittently given partial rotation a finger 86 fixed outwardly beyond the ratchet is caused to move around therewith until it presently lifts the pawl 82 and thereby precludes the further functioning thereof. The initial radial position of the finger 86 may be adjusted by means of a suitable set screw 87. In this manner a cessation of the automatic upward feed of the chuck is automatically accomplished 100 after which final calibration must be resorted to. The pawl is provided with an outwardly projecting pin 88 by means of which it may be manually lifted whenever it is desired to manipulate the feed of the chuck through the agency of a suitable handle 89 on the outer end of the shaft 78.

It is evident that my machine, besides effecting the rotation of both the tool and work, enables both cross-travel and an upward feed of the latter to be automatically accomplished. More than that, various adjustments are provided for prescribing the range of certain actions and besides an automatic throw-off attachment for limiting the effective operation of the automatic feed movement.

I claim:

1. A grinding machine comprising a wheel mounted to rotate in a fixed position, a rotary work chuck mounted for oscillatory movement relative to said wheel in a substantially horizontal plane therebelow and automatically operated means for imparting a step by step feed movement to said chuck.
2. A grinding machine comprising a tool, means for operating the same, a work support, means for moving said support rela-

tive to the tool in one direction and means for moving said support in another direction relative to said tool, one of said distinct support movements being adapted automatically to initiate the movement of the other.

3. A grinding machine comprising a tool, means for operating the same, a work support, means for effecting a second relative movement between said support and tool, 10 and means for effecting a third relative movement between said support and tool, one of said distinct support movements being adapted automatically to initiate the movement of the other intermittently at pre- 15 determined intervals.

4. A grinding machine comprising a rotary tool, a work chuck, means for feeding said chuck toward said tool, and means for oscillating said chuck across the rotary path 20 of said tool, said oscillating movement being adapted intermittently to initiate the feeding movement.

5. A grinding machine comprising a rotary abrading tool, a rotary work support, 25 mechanism for swinging said support bodily about an axis, means adapted to swing with said support for raising or lowering said support toward or away from said tool respectively, and a stop, said means including 30 a projecting part adapted during its swinging movement to engage said stop whereby automatically to actuate said means.

6. A grinding machine comprising a rotary abrading tool, a rotary work support, 35 mechanism for swinging said support bodily about an axis, means adapted to swing with said support for feeding said support substantially parallel with said axis, and an adjustable stop, said means including a projecting part adapted during its swinging 40 movement to engage said stop whereby said means is intermittently actuated.

7. A grinding machine comprising a rotary tool, a work chuck movable in operative 45 proximity thereto, means for effecting the compound movement of said chuck, and adjustable means for determining the duration of one component of movement.

8. A grinding machine comprising a rotary tool, a work support movable relative 50 to the said tool, means for effecting such movement, a chuck independently feedable upon said support, and an automatically operated device for effecting the throw-off of 55 said chuck feeding means.

9. A grinding machine comprising a rotary tool, an oscillatory work chuck, means for effecting such movement, said chuck being additionally movable toward and 60 away from said tool, and automatically operating means for feeding said chuck toward said tool and automatically operating means for limiting such feeding movement of said chuck.

10. A grinding machine comprising a rotary tool spindle, a pair of abrading tools thereon, a pair of rotary work supports, mechanism for simultaneously swinging said supports bodily across said tools respectively, duplex means adapted to swing with 70 said supports for moving said supports toward or away from said tools respectively, stops, said feeding means including projecting parts adapted during their swinging movement to engage said stops respectively 75 whereby said feeding means is intermittently actuated and an automatically operated throw-off device associated with said feeding means and adapted to cause a cessation of its intermittent action at a predetermined point of its advance. 80

11. A grinding machine comprising a rotary tool, a rotary work chuck, means for effecting the rotations of said tool and chuck, and automatically operating mechanism for alternately effecting the compound bodily 85 movement of one of said rotating parts first in arcuate and straight-line components of movement and then in only one of said paths. 90

12. A grinding machine comprising a rotary tool, a rotary work chuck, means for effecting the rotations of said tool and chuck, and means for effecting the reciprocal bodily movement of said chuck along 95 one path and simultaneously in a different direction.

13. A grinding machine comprising a substantially horizontal spindle, a pair of grinding wheels thereon, a pair of vertically movable work supports mounted so as to be oscillatory in horizontal planes below said wheels respectively and means for simultaneously moving said supports past the wheels respectively and vertically 105 to said planes.

14. A grinding machine comprising a substantially horizontal spindle, a pair of grinding wheels thereon, a pair of oscillatory work supports, means for simultaneously swinging said supports bodily past said wheels respectively, chucks movably carried upon said supports, and means for simultaneously feeding said chucks relative to said wheels. 115

15. A grinding machine comprising a bed, an abrading tool mounted for movement thereon, a work chuck mounted for movement upon said bed, means for operating said tool and chuck, and means for automatically effecting the compound movement of one of said operative parts toward the other and for causing a cessation of one component of such relative movement. 120

16. A grinding machine comprising a bed, 125 a rotary abrading tool mounted for movement thereon, a rotary work chuck mounted for compound bodily movement upon said

bed, means for rotating said tool and chuck, automatically operating means for feeding said chuck toward the tool and automatically operating means for terminating said feeding movement.

17. A grinding machine comprising a bed, an abrading tool mounted for movement thereon, a work chuck mounted for movement upon said bed, means for operating said tool and chuck and means for effecting an additional compound movement of said chuck comprising component movements along an arc and along a straight line respectively.

18. A grinding machine comprising a bed, an abrading tool mounted for movement thereon, a work chuck mounted for movement upon said bed, means for operating said tool and chuck, and means for effecting an additional compound bodily movement of said chuck comprising a component oscillatory movement and a component automatic feed movement toward said tool.

19. A grinding machine comprising a bed, a spindle, an abrading tool mounted thereon, means for rotating said spindle, a driving shaft, a pivotal shaft connected with said driving shaft, a work support oscillatorily mounted upon said bed about said pivotal shaft as an axis, means for oscillating said support, a chuck spindle rotatably mounted in said support so as to describe an arc of movement about the axis of the latter, a work chuck carried by said chuck spindle, mechanism operatively connecting said pivotal and driving shafts and adapted to rotate said chuck spindle, said chuck spindle being additionally mounted in said support so as to be capable of axial feed movement, feed mechanism operatively connected with said chuck spindle and adapted to effect its axial movement and means for actuating said feed mechanism.

20. A grinding machine comprising a bed, a horizontal spindle, an abrading tool mounted thereon, means for rotating said spindle, a driving shaft, a vertical pivotal shaft connected with said driving shaft, a work support oscillatorily mounted upon said bed about said pivotal shaft as an axis, means for oscillating said support, a track upon which the free end of said support may travel, a vertical chuck spindle rotatably mounted in said support so as to describe an arc of movement about the axis of the latter, a work chuck carried by said chuck spindle, mechanism operatively connecting said driving and pivotal shafts and adapted to rotate said chuck spindle, said chuck spindle being additionally mounted in said support so as to be capable of axial feed movement, feed mechanism operatively connected with said chuck spindle and adapted to effect its axial movements and means for

actuating said feed mechanism intermittently, including a stop on said bed and a member operatively connected with said feed mechanism and adapted to engage such stop.

21. A grinding machine comprising a bed, a spindle, an abrading tool mounted thereon, means for rotating said spindle, a driving shaft, a pivotal shaft connected with said driving shaft, a work support oscillatorily mounted upon said bed about said pivotal shaft as an axis, means for oscillating said support, a chuck spindle rotatably mounted in said support so as to describe an arc of movement about the axis of the latter, a work chuck carried by said chuck spindle, mechanism operatively connecting said pivotal and driving shafts and adapted to rotate said chuck spindle, said chuck spindle being additionally mounted in said support so as to be capable of axial feed movement, feed mechanism operatively connected with said chuck spindle and adapted to effect its axial movement and means for actuating said feed mechanism intermittently including a stop adjustably secured to said bed, a member operatively connected with said feed mechanism and adapted to engage such stop, a ratchet, and a pawl carried upon said member in engagement with said ratchet.

22. A grinding machine comprising a bed, a spindle, an abrading tool mounted thereon, means for rotating said spindle, a driving shaft, a pivotal shaft connected with said driving shaft, a work support oscillatorily mounted upon said bed about said pivotal shaft as an axis, means including a shaft connected with said driving shaft and an oscillating device upon said bed for oscillating said support, a chuck spindle rotatably mounted in said support so as to describe an arc of movement about the axis of the latter, a work chuck carried by said chuck spindle, mechanism operatively connecting said pivotal shaft and adapted to rotate said chuck spindle, said chuck spindle being additionally mounted in said support so as to be capable of axial feed movement, feed mechanism operatively connected with said chuck spindle and adapted to effect its axial movement, means for actuating said feed mechanism intermittently including a stop on said bed and a member operatively connected with said feed mechanism and adapted to engage such stop, a ratchet, a pawl, means for adjusting the throw of said oscillating device, and throw-off means for automatically disconnecting said ratchet and pawl.

23. A grinding machine comprising a bed, a rotary tool spindle, a rotary work chuck spindle, and mechanism for progressively feeding said chuck spindle axially.

24. A grinding machine comprising a bed, a rotary tool spindle, a work support, a

chuck spindle rotatably mounted thereon, intermittently operating mechanism for progressively feeding said chuck spindle axially and means for swinging said support about an axis.

25. A grinding machine comprising a bed, a rotary tool spindle, a work support oscillatorily mounted on said bed, a chuck spindle rotatably mounted thereon, mechanism for feeding said chuck spindle axially a predetermined definite distance and means for simultaneously oscillating said support and actuating said feed mechanism.

26. A grinding machine comprising a bed, a rotary tool spindle, a work support oscillatorily mounted on said bed, a chuck spindle rotatably mounted thereon, mechanism for feeding said chuck spindle axially and means for simultaneously oscillating said support and intermittently actuating said feed mechanism, said means including an automatically operating throw-off device whereby to determine the cessation of said feed actuation.

25 27. A grinding machine comprising a bed provided with a track, a rotary tool spindle, and a work support pivoted upon said bed and adapted to oscillate upon said track.

28. A grinding machine comprising a bed provided with a track, a rotary tool spindle, a work support pivoted upon said bed and having a lateral extension, a chuck upon said extension and adapted to describe an arc, and a projecting member carried by said extension and adapted to ride upon said track whereby to relieve the strain at said pivot.

29. A grinding machine comprising a bed provided with a track, a rotary tool spindle, a work support pivoted upon said bed and adapted to oscillate upon said track having a lateral extension, means for actuating said support, a chuck upon said extension and adapted to describe an arc, a roller yieldingly carried by said extension and adapted to ride upon said track whereby to relieve the strain at said pivot, said support actuating means including an adjustable device whereby to vary the length of the arc described.

30. A grinding machine comprising a bed, a rotary tool spindle, a work support pivoted upon said bed and adapted to oscillate upon said track having a lateral extension, means for actuating said support, a rotary chuck spindle in said extension, a chuck upon said spindle and adapted to describe an arc along with said extension, said support actuating means including a heart shaped cam and an adjustable rocking device for regulating its throw, and mechanism including a shaft positioned at said support pivot for rotating said chuck spindle.

31. A grinding machine comprising a bed, an abrading tool operatively mounted

thereon, a work support pivotally mounted upon said bed and fashioned with a lateral extension, and mechanism for swinging the latter about its pivot and including a shaft, a cam thereon, a member pivotally mounted upon said bed and carrying a part adapted to ride around said cam so as to rock said member, and an adjustable connection between said member and support extension.

32. A grinding machine comprising a bed, an abrading tool operatively mounted thereon, a work support pivotally mounted upon said bed and fashioned with a lateral extension, and mechanism for swinging the latter about its pivot and including a shaft, a cam thereon, a structure pivotally mounted upon said bed and carrying a part adapted to ride around said cam so as to rock said structure, a member adjustably connected with said structure, means for effecting such adjustment, and a link articulating with said member and with said work support extension.

33. A grinding machine comprising a bed, an abrading tool operatively mounted thereon, a work support pivotally mounted upon said bed and fashioned with a lateral extension, and mechanism for swinging the latter about its pivot and including a shaft, a heart-shaped grooved cam thereon, a hollow structure pivotally mounted upon said bed and carrying a roller adapted to run in the groove of said cam so as to rock said structure, a toothed member adjustably mounted in said structure, means including a gear for effecting such adjustment, a link articulating with said member and with said work support extension and means for varying the point of articulation of said link with said extension whereby to locate the throw of the latter at the proper position.

34. A grinding machine comprising a bed, an abrading tool movably mounted thereon, a work support movably mounted upon said bed, a chuck movably mounted upon said support, means for actuating said tool, said support and said chuck, said chuck moving means being automatically operated by the movement of said support, and distinct adjustable means for limiting the movements of said support and for determining the duration of said automatic chuck movement.

35. A grinding machine comprising a bed, a rotatable abrading tool movably mounted thereon, a rotatably mounted chuck adapted for compound movement relative to said bed, means for rotating said tool and said chuck, and mechanism for simultaneously actuating said chuck in two distinct directions and in one of such directions automatically.

Signed by me this 16th day of August, 1917.

FRANK G. HOLLAND.
